DEVICE FOR PROCESSING X-RAY FILM

Frank E. Corbett, Franklin Square, N.Y., assignor to the United States of America as represented by the Secretary of the Army

Filed May 13, 1966, Ser. No. 549,949

7 Claims. (Cl. 95—89)

ABSTRACT OF THE DISCLOSURE

A photographic apparatus for processing a composite X-ray film assembly of the type embodying pods of processing chemicals which are released by compression and spread throughout an exposed photosensitive area. The apparatus consists of a pair of pressure-bearing rollers between which the X-ray film assembly moves, which rollers supply the necessary compressive force to release the chemicals from the pods. A mechanism consisting of cams, cam followers, and resilient biasing members are provided to separate the rollers and release the pressure therebetween as the trailing edge of the film passes through to prevent smearing of the processing chemicals at the trailing edge.

The invention described herein may be manufactured and used by or for the Government for governmental purposes without payment to me of any royalty thereon.

This invention relates to a mechanism for processing X-ray film of the type containing pods of processing chemicals spaced throughout its surface.

Under field conditions the availability of electricity becomes problematical. Accordingly, it is desirable to provide means for developing the film entirely independently of electrical power.

One purely mechanical method of processing film of the type described herein involves manually pulling the film between a pair of pressure bearing rollers whereby the developing chemicals encapsulated within the film surface are broken and spread throughout the entire surface. As the trailing edge of the film passes through the rollers, the developing chemicals will escape onto the rollers, thereby hindering future developing operations. Further, manual manipulation of the film being processed causes non-uniformity in the spreading of the developing chemicals. Often a smeared, finished product results because of the inherent defects of the desired operation.

The object of this invention is to provide means for removing the pressure between the pressure bearing rollers as the trailing edge of the film passes through, to thereby prevent the smearing at the trailing edge. Further, by removing the pressure between the rollers and by separating the rollers, the developing chemicals will not escape onto the rollers.

Accordingly, a further object is to provide means for separating the rollers as the trailing edge of the film passes through the rollers.

Another object is to provide mechanical means for moving the film between a pair of pressure bearing rollers, thereby obviating the necessity for pulling the film between the rollers manually.

Another object is to provide portable light shields to further increase the overall mobility of this invention. These and further objects will become apparent from the following description wherein:

2

FIG. 1 is a perspective view of the processing mechanism;

FIG. 2 shows the details of the driving gear arrangement for the lower roller;

5 FIG. 3 is a side view of the processing mechanism with the solid line portion showing the cross-arm member 14 engaged by the cross-bar lock assembly 11, and the broken lines showing the cross-arm member disengaged; and

10 FIG. 4 shows the processing mechanism mounted within a housing which has light shields attached.

Basically, the invention involves a driving drum 2 driving a shaft which connects to one of the pressure bearing rollers 15. A storage drum 102 houses a flat constant tension spring 1. One end of spring 1 is attached to the storage drum 102; the other end is attached to the driving drum 2. As the spring 1 unwinds onto the storage drum 102, it causes the driving drum to drive the roller 15. As the driving drum revolves, co-action between an indent or cam means 75 on a flange 65 of the winding drum and cam follower 21 unlocks a cam follower arm latch 22 which in turn allows the upper roller 16 to spring away from the lower roller 15.

25 The driving drum 2 has a circular flange member 4 about its circumference as shown in FIG. 2. The flange member 4 has an internal ring gear. Also, an indent or cam means 75 is machined into the outer periphery of the flange member 4. The internal ring gear of flange 4 engages a spur gear 52 mounted on a spur gear hub 53. A spur gear shaft 54 connects to the hub 53. A main frame bearing 55, a spring 56, and coupling 57 are mounted upon the spur gear shaft 54. When the coupling 57 is manually forced to the right, the lower roller turns freely; this facilitates cleaning. The lower roller 15 is mounted upon a hexagonal lower roller shaft 59. A pillow block 60 is mounted upon the roller shaft 59. Thus, as the flange member 4 revolves, a corresponding force is transmitted to lower roller 15.

30 The constant tension spring 1 stored on drum 102 is wound onto the driving drum 2 by turning knob 34. A ratchet 42 and pawl 38 prevent the release of the spring wound driving drum 2. The circular ratchet 42 is firmly secured to the main frame 5. The pawl 38 is pivotally mounted on circular plate 40; the plate is joined to the turning knob 34 by means of two machine screws 31. A circular cam 35, having a notched portion, is firmly secured to the driving drum shaft 54 by a cam retaining screw 32 and a washer 33. The cut-out notched portion of cam 35 co-acts with a tooth 45 on cam release member 37; the cam release 37 is pivotally mounted on plate 40. Arm 46 of the cam release member protrudes through a slot 49 on the turning knob. As the turning knob 34 is rotated the tooth 45 is forced into the cut-out portion of cam 35 by the tension of a cam release spring 39. The drum 2 can then be wound. Stop spring 81 is engaged as the drum 2 being wound reaches its limit of travel. The driving drum 2 unwinds counterclockwise in FIG. 3.

35 When the cam release arm 46 is depressed, tooth 45 is freed from the cut-out portion of cam 35, thereby allowing the cam and driving drum shaft 54 to rotate freely. The turning knob 34 and plate 40 are restricted by the 40 action of the pawl 38 and ratchet 42.

The driving drum 2 has an internal ring gear member 4 upon whose periphery an indent or cam means 75 is machined. An arm 22 mounting a bearing 21 which acts as a cam follower, is pivotally mounted to the main frame 5 by shaft 18, and is positioned to travel along the outer periphery of the ring gear member 4 and the drum flange 65. A pressure tab 19, tie bar 17, shaft 18, and cross-bar lock assembly 11, 76, apply pressure to locking pin 24 which is attached to cross-bar 14. The lock assembly consists of two members, one pivoted on the other. The lower member 76 is rotatably mounted on shaft 18. The upper member 11 is pivotally mounted on and operates independently of lower member 76. The upper member 11 has a projection 77 as shown in FIG. 3. As the cross-bar 14 is forced downward, a pin 24 co-acting with the projection 77 of the upper member 11 causes the upper member to pivot, thereby allowing the pin 24 to pass the projection. As the pin 24 passes the projection, the cross-bar 14 is locked into its horizontal position as shown by the action of spring 6 forcing the upper cross-bar lock assembly member 11 to its original position as shown in FIG. 3.

At all times the cross-bar lock assembly is forced away from the main frame 5 by a force exerted by cam follower 21, through arm 22, through shaft 18, through pressure tab 19 to tie bar 17. This condition is opposed by a counterforce from spring 6, which draws the entire locking assembly toward the main frame 5 at the instant the cam follower 21 enters the indent or cam means 75. This instantaneous inward motion releases pin 24 from projection 77. Cross-bar 14, which mounts the upper roller 16, springs free, by the action of spring 80, thereby eliminating the pressure between the upper and lower rollers.

One end of the upper roller mounting arm 12 is pivotally mounted to the main frame 5; the other end is pivotally mounted on the cross-bar arm 10. Metering pressure of the upper roller 16 is controlled by a spring loaded screw 9. The chemical pod breaking pressure is controlled by the spring loaded screw 7. The cross-bar is sprung away by means of the loop of spring wire 80 positioned between the main frame 5 and the cross-bar arm 10.

One complete sequence of operation involves winding the driving drum 2 in the manner previously described. Next cam release 37 is depressed, thereby allowing the tooth 45 to release cam 35. The driving drum 2 being thus freed, is forced to revolve by the action of spring 1 unwinding from the driving drum 2 onto the storage drum 102. Ring gear 4 in turn drives the lower roller 15 by engaging the spur gear 52. In this manner, the film to be developed is pulled through the compressed rollers. When the cam follower 21 engages indent or cam means 75 the tension of spring 6 causes the cross-bar locking assembly (consisting of upper member 11 and lower member 76) to move toward the main frame 5 thereby allowing the cross-bar 14 to spring free by virtue of spring 80. The upper roller disengages entirely from the lower roller by means of the pivot arrangements previously described.

FIG. 4 shows the entire film processing mechanism contained in a case having openings on the two sides which are parallel to the surface of the rollers. Attached to the openings in light, tight relation are opaque, flexible and portable light trap coverings 101 and 105. One of these coverings 101 contains the loaded cassette before and the other 105 to accept the developed film packet after it passes through the rollers. After a predetermined time interval, the film is removed from the covering receiving the developed film through an opening in the covering.

I claim:

1. A device for processing film comprising:
  - (a) a pair of pressure bearing rollers supported within a housing;

- (b) means for driving a fixed one of said pair of rollers;
  - (c) cam means associated with said driven one of said rollers;
  - (d) a cross-bar member carried by said housing and mounting a movable one of said rollers;
  - (e) resilient means positioning said cross-bar member to produce pressure;
  - (f) latching means for said cross-bar;
  - (g) resiliently biased release mechanism connected to said latching means; and
  - (h) a cam follower arm having a cam follower at one end thereof coacting with said cam and the other end thereof connected to said release mechanism whereby when said cam follower engages said cam, said release mechanism trips said latching means to permit said cross-bar to move and separate said movable roller from contact with said fixed roller.
2. The device of claim 1 wherein said means for driving said rollers comprises:
    - (a) a spring driven drum having a flanged rim;
    - (b) an internal ring gear attached to said flanged rim; and
    - (c) a spur gear coacting with said ring gear driving said fixed roller.
  3. The device as stated in claim 1 further comprising a housing in which said device is suitably mounted, and light shields attached to each of the sides of said housing.
  4. A device for processing film comprising:
    - (a) a main frame;
    - (b) a cross-bar and arm assembly, spring loaded and pivotally mounted on said main frame;
    - (c) an upper roller mounted on said cross-bar and arm assembly;
    - (d) a driving drum having a flanged rim, said flange having a cut-away indent portion, said drum mounted on said main frame;
    - (e) means for rotating said driving drum;
    - (f) a lower roller driven by said driving drum;
    - (g) a cam follower shaft mounted on said main frame;
    - (h) a cam follower communicating with the outer perimeter of said flange including said indent, and mounted on the cam follower shaft;
    - (i) a cross-bar lock assembly including a lower member mounted on said cam follower shaft and an upper member pivotally mounted on said lower member, said upper member having a cut-away hooked portion for locking said cross-bar to produce pressure between said upper and lower rollers;
    - (j) a spring between said upper member and said main frame providing tension for locking said cross-bar;
    - (k) means for releasing said cross-bar lock assembly when said cam follower engages the indent, thereby forcing the cross-bar lock assembly away from the main frame and freeing said cross-bar and arm assembly.
  5. The device as set forth in claim 4 wherein the means for rotating the driving drum comprises:
    - (a) a storage drum mounted on the main frame;
    - (b) a constant tension spring one end attached to said storage drum, the other end attached to said driving drum;
    - (c) means for winding said spring onto said driving drum;
    - (d) means for releasing said driving drum when wound, thereby allowing the spring to unwind onto the storage drum to produce a force against said driving drum.
  6. The device as stated in claim 4 wherein the means for releasing said cross-bar lock assembly comprises:
    - (a) a release arm tie-bar connected to said lower member of the cross-bar lock assembly;
    - (b) a pressure tab mounted upon said tie-bar and said cam follower shaft, said pressure tab translating the force applied to the cam follower shaft to the tie-bar

arm when said cam follower engages said indent portion, said tie-bar forcing the cross-bar lock assembly away from said main frame thereby freeing said cross-bar and arm assembly.

7. The device as recited in claim 6 further comprising a housing in which said device is suitably mounted; and opaque, flexible and portable shield members attached to each of the sides of said housing and communicating with said rollers through openings in said housing parallel to the direction of said rollers.
